D23-346

EX

D7463

OR D 1,041

No 1041.

Design

IRON-SIDES STOVE

— Designed by Steffe Horton —

— & Currie —

— Assignors to —

— STUART & PETERSON —

Patented Aug. 17. 1858.

UNITED STATES PATENT OFFICE.

JACOB STEFFE, JAMES HORTON, AND JOHN CURRIE, OF PHILADELPHIA, PENNSYLVANIA, ASSIGNORS TO DAVID STEWART AND RICHARD PETERSON, OF SAME PLACE.

DESIGN FOR A STOVE.

Specification forming part of Design No. 1,041, dated August 17, 1858.

To all whom it may concern:

Be it known that we, JACOB STEFFE, JAMES HORTON, and JOHN CURRIE, of the city of Philadelphia, in the county of Philadelphia and State of Pennsylvania, have invented or produced a new and original Design for a Stove, termed the "Ironsides;" and we do hereby declare the following to be a full and exact description of the same, reference being had to the accompanying drawing, which forms a part of this specification, and which represents the said stove in perspective.

A is the bottom plate of the stove, B the base, C the body, D the capital, and E the cap. The portion of the plate A on which the base rests is edged with a plain molding, and the portion which forms the hearth has foliated ornaments. The base B consists of two moldings, the lower molding being ornamented with a series of ribs, and terminating at its junction with the plate A in a denticulated beading. The upper molding, which is also ornamented with a series of ribs, is separated from the lower molding by a plain belt, a.

The body C is surrounded by an ornamental belt, above and below which are series of ribs. Between the capital D and the body, and forming part of the latter, is a molding, d, ornamented with flutes, the lower portion of the capital being a similar molding inverted, and the upper portion of the capital a molding with ornaments of a different character. The cap E is a plain plate edged with an ornamental molding.

We claim—

The combination and arrangement of ornamental figures and forms, represented in and by the accompanying drawing, and forming together an ornamental design for a stove.

In testimony whereof we have signed our names to this specification before two subscribing witnesses.

JACOB STEFFE.
JAMES HORTON.
JOHN CURRIE.

Witnesses:

HENRY HOWSON,
HENRY ODIORNE.